UNITED STATES PATENT OFFICE.

CLARA BIRCHARD LAMBERT, OF PASADENA, CALIFORNIA.

MOP WRINGER.

Application filed September 29, 1927. Serial No. 222,841.

The present invention has reference to mop construction and aims to provide novel means whereby a mop may be wrung with facility.

Another object of the invention is to provide means to be secured to the scrub pail and to which the mop is temporarily secured during the wringing operation, the means secured to the scrub pail being such that it will not interfere with the mop being placed into the scrub pail to wet the mop.

A still further object of the invention is the provision of an attachment of this character which may be readily and easily secured to the usual mop construction or mop webbing material.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a plan view illustrating the mop as positioned over a bucket preparatory to wringing.

Figure 2 is a side elevational view thereof.

Figure 3 is an elevational view illustrating the mop folded for mopping purposes.

Figure 4 is an elevational view showing the clamp employed for securing the mop to the bucket or pail for wringing.

Referring to the drawing in detail, the device includes a member 5 and a member 6, the member 5 constituting a length of heavy wire material bent to provide a loop 7, the ends thereof being twisted around each other defining a shank 8 to be positioned in a bore formed in one end of the usual mop handle 9.

The member 5 is further secured to the handle by means of the arms 5' that have openings at their ends to receive the ends of the member 5 as shown by Figure 1.

The member 6 is also formed of a length of heavy wire material bent in such a way as to provide a loop 10 or eye and a pair of inwardly extended overlapping arms 11

constructed in such a way that the webbing material forming the mop may be slipped therebetween and held in the main portion of the member 6 as clearly shown by Figure 1 of the drawing.

The reference character 12 indicates the mop webbing material which is formed into loops as shown by the drawing so that they may be readily and easily secured to the members 5 and 6.

Secured to the handle 9 at a point adjacent to the inner end thereof is a hook 13 designed to accommodate the loop or eye 10 when the mop is being used for mopping a surface. Used in conjunction with the mop, is a clamp 14 which is designed to be secured to the scrub pail, there being provided winged screws extending through the body portion of the clamp and contacting with the pail to secure the clamp in position.

Extending upwardly from the clamp is a finger 15 which is curved in such a way as to insure against the eye or loop 10 becoming displaced during the wringing operation. In connection with the finger 15, it might be stated that when it is desired to wring the mop, the eye or loop 10 is positioned over the finger and the handle portion 9 twisted, the water wrung from the mop dropping into the pail.

It will also be seen that due to this construction, the mop may be wrung by an attachment carried by the scrub pail, eliminating the usual obstructions such as wringing rolls or the like carried by the pail and which form a part of the usual wringer employed in connection with scrub pails.

I claim:

1. A mop embodying mop webbing material, a length of wire material bent to provide an elongated loop through which the mop webbing material extends at one end of the mop, a tubular member to receive the handle of the mop, laterally extended arms formed on the tubular member, means for connecting the arms to the ends of the elongated loop, and a loop member through which the mop webbing material extends at the opposite end of the mop.

2. A mop embodying mop webbing material, a length of wire material bent to provide an elongated loop, said mop webbing

2

material extending through the loop, a member through which the opposite ends of the mop webbing material extends, said member having a loop formed intermediate the ends thereof, a handle to which the elongated loop member is secured, a tubular member on the handle, arms extending from the tubular member and having connection with the

elongated loop member, and a hook on the tubular member to receive the second mentioned loop to hold the mop webbing material in a folded condition. 10

In testimony that I claim the foregoing as my own, I have hereto affixed my signature.

CLARA BIRCHARD LAMBERT.
